DRAINAGE ASSEMBLY

Hans Richter, Bremen, Germany

Application November 25, 1952, Serial No. 322,417

Claims priority, application Germany November 29, 1951

5 Claims. (Cl. 137—177)

The invention relates to a drain of condensed water for steam plants in which the condensed water is drained from the steam chamber through a nozzle.

The purpose of the nozzle is based on the known fact that only a small amount of steam, viewed from the weight standpoint can pass through a nozzle, but a much larger amount of condensed water can pass therethrough. If the nozzle is well adapted to the condensed water to be drained with respect to its passage capacity, and the flow of condensed water remains substantially uniform, the passage of steam can be entirely prevented. Also, under most unfavorable operating conditions, namely where no condensation occurs, only a very small amount of steam can leave.

Inasmuch as the nozzle is quite insensitive, and, also drains air and gases, it offers numerous advantages, but it presupposes a correctly selected nozzle width.

Thus, the invention relates to an installation which enables in an exact manner to permit a subsequent test of the nozzle bore, and to also allow a continuous checking of the operation if a change of nozzle unit becomes necessary.

The instant invention materially improves the prior units by providing the collecting chamber for foreign matter with a partition or wall which is so arranged that the lower edge of the partition or wall is at a lower level in the chamber than the inlet and outlet openings as well as the inlet mouth of the nozzle element.

In the case of horizontally disposed conduits, the partition or wall is vertically mounted within the chamber while in the case of vertically or angularly mounted conduits, the partition is disposed angularly respecting the inlet and outlet openings and in such installations, it has been found desirable to employ two spaced partitions.

More specifically, the partition is disposed within the chamber forwardly of the nozzle element or between the nozzle element and the inlet so that the waste water flowing through the assembly must initially pass the partition before reaching the inlet mouth of the nozzle element. To permit the current of condensed water and steam about the lower edge of the partition to be seen, one or more sight glasses are incorporated with the lateral walls of the chamber and preferably opposite to each other, with the center of each sight glass lying opposite the lower edge of the partition. Furthermore, the entrance of the nozzle extends sufficiently far into the chamber to permit the same to be directly viewed through such sight glasses.

So long as condensed water flows off through the nozzle element, the water level will be at least as high as the lower edge of the partition or wall but should the nozzle element be too large or should steam be present in the flow, the steam can only escape to the nozzle by pressing the water level below the lower edge of the partition and the greater the distance between such water level and the lower edge, the greater the steam passage whereby it is possible to ascertain whether the loss of steam is great

2

or small. Due to the size of the sight glasses, and the relationship of the nozzle with respect to the chamber, the operation of the assembly can be continuously watched and make any replacement of the nozzle if the conditions warrant such replacement.

To facilitate the replacement of the nozzle element, the cleaning of the sight glasses, et cetera, a stop valve member may be installed in the inlet to the chamber thereby enabling such repairs or replacements to be effected during the operation of the installation.

If desired, a temperature measuring unit, such as a bimetal thermometer may be installed in the assembly at a point opposite to the outlet end of the nozzle element thereby permitting the temperature of the condensed water to be determined as it flows off. Since the temperature of the water drops during rising, this unit allows a speedy check of possible plugged conditions in the installation.

Since the bottom of the thermometer support is subjected to the direct action of the water jet emanating from the nozzle, a rapid transfer of heat occurs and a corresponding rapid rise of the thermometer.

The numerous objects and advantages of the present invention will become readily apparent from the ensuing description and the attached drawings.

In describing the invention in detail, reference will be had to the accompanying drawings forming part of this specification, wherein like reference characters indicate corresponding parts in the several views, and in which:

Figure 1 is a vertical sectional view of a drainage assembly embodying one form of the inventive concept.

Figure 2 is a view similar to Figure 1 illustrating a further embodiment of the invention.

Figure 3 is an elevational view, partly in cross-section of another embodiment wherein a stop valve is located in the inlet to the assembly, and,

Figure 4 is a vertical sectional view of the form used in vertical or angularly disposed conduits.

As shown in Figure 1, the assembly comprises a two part housing 10 including an upper member 11, a lower member 12 and securing means 13 providing a leak proof union between the two members. An inlet 14 and an outlet 15 are formed in the upper member 11, the respective elements being coupled to conduits, not shown.

The lower member 12 constitutes a collection chamber 16 for foreign matter and the securing means 13 is such that the lower member may be removed from the upper member for repair, cleaning purposes and the like. Integrally formed with the top wall of the upper part 11 and depending into the chamber 16 is a vertical partition or wall 17 and it will be noted that lower edge 18 of the partition terminates a substantial distance below the inlet and the outlet 14 and 15 respectively. Also, the edge 18 is of greater perimetric dimensions than the remainder of the partition and is substantially circular in cross-section. It has been determined that by thus forming the lower edge of the partition, the flow of the condensed water along the lower edge is particularly quiet.

As depicted in Figure 1, the outlet 15 is provided with an angularly disposed casing in which a nozzle 19 is removably mounted and inlet mouth 20 of the nozzle is located above the lower edge 18 of the partition. A ball 21 is lodged in the outlet of the nozzle and functions as a one way valve element. A manually operated actuator 22 is provided for the ball 21.

Thus, it will be appreciated that the assembly includes but few essential working parts thereby permitting the assembly to be inexpensively manufactured and the repair and replacement costs can be maintained at a minimum.

The water entering the assembly through the inlet 14 first fills the chamber 16 and continues to rise until the

level has reached the inlet mouth 20 of the nozzle. The condensed water then enters the nozzle and is discharged in jet form into the outlet opening 15 leading to the discharge conduit.

During operation, the lower edge 18 of the partition 17 is deeply immersed in the water and if the cross section of the nozzle is too large not only condensed water but also steam will drain off. The steam cannot enter the mouth 20 directly because of the partition and must pass between the lower edge 18 and the water level. Thus, the steam applies a pressure to the water level and the level drops and the greater the amount of steam in the flow, the greater the fall of the water level.

As hereinbefore mentioned, the housing is provided with sight glasses to permit the inspection of the interior of the assembly and such sight glasses are shown at 23. The glasses are of such size and are so located in the housing walls that the lower edge 18 of the partition and the mouth end 20 of the nozzle 19 can be easily seen. Furthermore, the mid point of each glass 23 lies opposite to the lower end of the partition which means that the current of the condensed water and the steam about such lower end of the partition can be readily observed. Hence, the drop of the water level is readily visible through the sight glasses and the amount of steam in the flow can be quickly determined.

In the modification illustrated in Figure 2, the same reference characters are used with the exception they are primed. The primary difference resides in the fact that the nozzle 19' is mounted in the outlet 15' coaxially with the outlet instead of at an angle thereto. Also, the lower edge 18' of the partition 17' need not extend too deep into the chamber 16' so long as the edge is below the nozzle mouth 20' and the inlet 14' as well as the outlet 15'. Obviously, the steam cannot enter the nozzle directly from the inlet 14'.

This modification functions in the same fashion as Figure 1.

Figure 3 is also quite similar to Figure 1 and here again, the same characters are used although they are double primed. In this form, the inlet 14'' is provided with a seat 30 for cooperation with a manually operated valve 31 by means of which the flow into the housing 10'' can be arrested during the operation of the installation. Also, the nozzle 19'' is surrounded by a tubular screen or sieve 32 and the condition of the sieve can be ascertained through the sight glasses 23''.

Mounted above the outlet end of the nozzle 19'' in a suitable fitting 33 removably fixed in the upper wall of the member 11'' is a bi-metal thermometer 34 of convenient type and the lower wall of the fitting is closely adjacent the outlet of the nozzle 19''. Consequently, the water jet leaving the outlet of the nozzle impinges on the bottom of the thermometer fitting 33 and it is possible to speedily and accurately determine the temperature of the waste water.

Furthermore, the partition 17'' is not integrally formed with the upper member 11'' but rather is a separate element which is detachably affixed to the upper member as depicted at 35.

The operation of this embodiment is the same as that described in connection with Figures 1 and 2. However, the provision of the valve parts 30 and 31 permits the flow to be shut off to allow the assembly to be repaired, cleaned and the like.

To adapt the invention for use in special installations, such as vertically and angularly arranged conduits, the form shown in Figure 4 is employed. In this form, 40 indicates the housing, 41 and 42 the inlet and outlet to the housing respectively, 43 the nozzle in the outlet and 44 the partition arrangement generally.

The partition arrangement includes two spaced apart partitions 45 and 46 disposed within the chamber and these partitions are located at an angle of about 45°.

degrees to the inlet 41, outlet 42 or both. It will be observed that the partition 45 extends into the chamber obliquely from the inlet side whereas the partition 46 extends obliquely from the outlet side in parallelism to the partition 45 which in effect defines a circuitous path within the chamber.

The inner end of the partition 45 shown at 47 and the inner end of the partition 46 denoted 48 extend into the chamber so that the free end 47 lies somewhat beyond an imaginary prolongation of the obliquely located wall surface of the inlet 41 whereas the end 48 of the partition 46 is located outside of the imaginary prolongation of the wall surface of the outlet 42.

It is believed manifest from this description that the flow in the chamber cannot directly enter the nozzle mouth and this embodiment functions in a manner along the lines previously described.

Hence, in all of the forms disclosed, the lower edge of the partition or partitions is below the inlet and the outlet of the chamber as well as the nozzle. By the provision of the sight glasses in the housing walls, the interior of the assembly may be easily and readily viewed to ascertain the amount of steam present in the flow.

It is to be understood that the invention is not to be confined to any strict conformity with the showings in the drawings, but may be changed or modified so long as such changes or modifications mark no material departure from the salient features of the invention as expressed in the appended claims.

I claim:

1. A condensation drainer comprising a housing having a collecting chamber therein, a fluid inlet communicating with the chamber, a fluid outlet communicating with the chamber, a partition within the chamber between the fluid inlet and the fluid outlet extending transversely of the chamber, a nozzle having an inlet end and an outlet end, means mounting the nozzle in an inclined position relative to the partition with the outlet end in direct communication with the fluid outlet, a ball valve controlling the outlet end of the nozzle, and a free end on the partition beyond the inlet end of the nozzle, the fluid inlet and the fluid outlet to normally hold the water level without loss of vapor at such free end.

2. A condensation drainer as defined in claim 1 where in a temperature indicating device is supported by the housing above the outlet end of the nozzle so that the water emanating from the nozzle outlet end directly impinges upon the temperature indicating device to indicate the temperature of the water in the chamber.

3. A condensation drainer as defined in claim 2 where in a protective screen surrounds the nozzle and the fluid inlet is provided with valve means to arrest the fluid flow to the chamber.

4. A condensation drainer comprising a housing having a collecting chamber therein, a fluid inlet communicating with the chamber, a fluid outlet communicating with the chamber, a nozzle having an inlet end and an outlet end mounted within the chamber with the outlet end in direct communication with the fluid outlet, a partition within the chamber between the inlet end of the nozzle and the fluid inlet extending transversely of the chamber and having a free end beyond the inlet end of the nozzle, the fluid inlet, and the fluid outlet to normally hold the water level without loss of vapor at such free end, the fluid inlet and fluid outlet being in axial alignment and the inlet and outlet ends of the nozzle being in axial alignment with the fluid inlet and outlet.

5. A condensation drainer comprising a housing having a collecting chamber therein, a fluid inlet communicating with the chamber, a fluid outlet communicating with the said chamber and in axial alignment with the fluid inlet, a nozzle having an inlet end and an outlet end mounted in the fluid outlet with such ends in axial alignment with the fluid outlet, and at least one partition ex-

tending into the chamber between the nozzle inlet end and the fluid inlet at an angle of about 45 degrees with respect to the fluid inlet and fluid outlet and having a free end terminating beyond the inlet end of the nozzle to normally hold the water level without loss of vapor at said free end of the partition.
